UNITED STATES PATENT OFFICE.

ALEXANDER J. PANCRATZ AND FRANK J. PANCRATZ, OF DENVER, COLORADO.

STATION-INDICATOR.

1,036,892.

Specification of Letters Patent. Patented Aug. 27, 1912.

Application filed October 27, 1909. Serial No. 524,910.

To all whom it may concern:

Be it known that we, ALEXANDER J. PANCRATZ and FRANK J. PANCRATZ, citizens of the United States of America, residing at 5 Denver, in the county of Denver and State of Colorado, have invented certain new and useful Improvements in Station-Indicators, of which the following is a specification.

This invention relates to certain new and 10 useful improvements in apparatus by which the stations along a line of railway or the streets intersected by a car-line, will be successively displayed at one or more points in the vehicle so as to be plainly visible to the 15 passengers.

The object of the present invention which is more particularly adapted for use on electric railways, resides in the provision of a 20 system of coöperative devices which are actuated by the closing or opening of an electric circuit which connects with the source of electricity by which the vehicles moving along said railways, are impelled, and which 25 serve to intermittently move a curtain upon which the street-names are placed in successive order, a distance equal to that between two consecutive names.

The invention consists to this end, of a 30 motor by which the curtain is actuated, means whereby the movement of said curtain is automatically arrested after it has traveled the required distance, an apparatus which will automatically break the motor-circuit should the contact by which it 35 was completed, be prolonged beyond a predetermined period, switches controlling the various circuits included in the system, a contact device by which the operating circuit is closed or broken, a non-reductive resistance coil and such other electrical devices as are essential to assure the successful and positive operation of the system.

When the apparatus is used in connection 40 with an electric railway operating by the overhead wire-system, the circuit or circuits in which said apparatus is included, may be closed or opened by coöperative contact devices respectively secured on the means by which the overhead wire is supported and 45 on the trolley pole which connects said wire with the motor of the car; on cars impelled by the 3rd rail system, these contact-devices are connected with the third rail and

5 with the contact arm projecting from the vehicle, while on storage-battery cars, or, if so desired on the other cars as well, the operating circuit of our system may be controlled by the motorman in charge of the vehicle.

An embodiment of our invention has been illustrated in the accompanying drawings 60 in the various views of which like parts are similarly designated and in which—

Figure 1, shows a diagrammatical representation of the electric circuits and coöperative devices employed in the system, 65 Fig. 2, a plan view of the operating mechanism by which the movements of the indicative curtain are controlled, Fig. 3, a section taken along the line 3—3 Fig. 2, looking in the direction of the arrow *a*, Fig. 4, a 70 similar section taken along the same line but looking in the direction of the arrow *c*, Fig. 5, a transverse section along the line 5—5 Fig. 2, Fig. 6, a similar section along the line 6—6 Fig. 2, Fig. 7, a view showing 75 a portion of an over-head wire and the trolley engaging the same, together with the coöperative devices by means of which the operating circuit of our system may be closed, Fig. 8, a section taken along the line 8—8 80 Fig. 7, Fig. 9, a view of the overhead wire and trolley, adapted to open instead of close the circuit above referred to, Fig. 10, a diagrammatic view showing modifications in the electric circuit and the main switch when 85 the arrangement shown in the preceding figure is employed, Fig. 11, a side view of the contact-devices employed in connection with a third-rail system of impelling electric railway cars, Fig. 12, a section taken 90 along the line 12—12 Fig. 11, Fig. 13, a sectional fragmentary view of a car showing the mechanical elements included in the system in their relative positions, Fig. 14, a section taken along the line 14—14 Fig. 13, Fig. 95 15, a transverse section through the curtain-supporting and winding apparatus taken along the line 15—15 Fig. 14 and drawn to an enlarged scale, Fig. 16, a section taken along the line 16—16 Fig. 15 and Fig. 17, a 100 section taken along the line 17—17 Fig. 15.

Our improved indicating apparatus comprises two elements A and B, the former of which is designed to support and display the movable curtain upon which the street- 105 names are placed, while the other is adapt-

ed to actuate and otherwise control the movements of the mechanism included in the first named element.

The element A consists of a suitable casing 2 in which four rollers 3, 4, 5 and 6 are revolutely supported at diagonally opposite points.

The curtain 7 upon whose outer surface the names of the streets are successively displayed, is secured at its extremities, upon the winding rollers 3 and 4 and is stretched around the idle rollers 5 and 6, so that its portion in between the latter extends vertically before a window 8 in the front side 15 of the casing, through which the street names are exposed to view.

The roller 3 is revolutely mounted upon an axle 9 and has an axial recess for the reception of a coiled spring 10 one end of which is secured to said axle while the opposite extremity is connected with the roller.

The winding roller 4 which is disposed subjacent the spring-roller 3, carries upon its shaft 13 a sprocket wheel 12 by means of which the curtain-moving element A is connected with the operating element B. The roller 4 which is loosely mounted upon the shaft 13, is connected with one member 30 of a clutch 14, the other member of which is slidably mounted upon the shaft, to rotate in unison therewith, and is supported on a rocker arm 15 which connects by means of a link 16 with an operating lever 17.

A brake-arm 18 is connected with the rocker arm 15 to arrest excessive movement of the roller 14 by engagement with the peripheral surface of a flange 19 forming part thereof.

A ratchet wheel 20 mounted upon the shaft 13, is engaged by a pawl 21 to prevent retrograde motion of the roller, while a coiled spring 22 surrounding the shaft, serves to resiliently maintain the moving clutch member and the therewith associated parts in their normal position.

The mechanism above described is provided to wind the curtain 7 from one roller onto the other when the car, having reached 50 the terminus of the line, returns along the same route.

The spring 10 in the roller 3, having previously been wound by any suitable means, is held in tension through the instrumentality of the curtain, by means of the ratchet and pawl associated with the roller 4, whose clutch member, it will be understood, is normally engaged by the clutch-member on the arm 15 through the expansive action of the spring 22.

To re-wind the curtain 7 upon the roller 3 the clutch members are disengaged by placing the lever 17 and the therewith associated parts in the position shown in Fig. 65 17 of the drawings, thus allowing the roller

14 to rotate about the shaft 13 with the result that the spring 10 is released and by its torsional action, imparts a rotative movement to the roller 3 upon which the curtain is wound.

The idle roller 5 is composed of insulating material and is provided with two series of alternately disposed metallic strips 23, which project from its ends oppositely along its peripheral surface and terminate a short distance from the opposite ends. Each series of strips is integral with a cap 24 into which the respective end of the roller is inserted and which terminates in a sleeve 25, surrounding the shaft 26 upon which said roller is mounted. The two sleeves of the caps 25, are in constant engagement with contact brushes 27 which being mounted upon the casing 2, constitute the terminals of an electric brake-circuit included in our system as will herein-after be described. The means for completing this circuit are provided by metallic plates 28 which being preferably secured upon the inner surface of the curtain are adapted to simultaneously engage two of the alternate strips 23 of the two series placed upon the periphery of the roller 5, when passing around the latter.

To increase the commercial value of the apparatus, the various rollers may, if so desired, be divided by flanges 29 into two sections upon one of which the street-name-displaying curtain 7 is supported, while the other carries a similar curtain for the display of advertising matter.

The operating mechanism comprised in the element B of the system, includes an electric motor 30 whose shaft 31 carries a worm 32 which engages a wormwheel 33 105 loosely mounted upon a transverse shaft 40. A clutch 34 is composed of two members one of which is connected with the wheel 33 while the other is slidably mounted on the shaft 40 so as to rotate in unison therewith and is movably supported upon the upper end of a rocker arm which is pivotally mounted in a bearing 36 upon the floor of the casing 37 inclosing the operating mechanism. The arm 35 connects with the movable core of a solenoid 38 and with the extremity of a spring 39 which serves to maintain it in its normal position when the two members of the clutch 34 are out of engagement. The shaft 40, which is revolutely mounted on standards 41, carries upon one of its extremities, which protrudes beyond the casing 37, a sprocket wheel 42 which, when the apparatus is in operation, connects with the corresponding wheel 12 110 of the element A by means of a chain 43 (see Fig. 13). An electro-magnetic brake 44 including a solenoid 45 and the therewith associated co-operative shoes 46, is disposed so as to act upon a brake wheel 47 on the

motor shaft 31 for the purpose of arresting the rotatory movement thereof after the curtain 7 has traveled a predetermined distance over the rollers comprised in the element A. 5 The shoes 46 of the brake 44 are mounted at opposite sides of the wheel 47, upon levers 46^a which are fulcrumed at their lower extremities while their upper ends are connected with the core of the solenoid 45 so as to be drawn together during longitudinal movement of the same. A spring 46^a is applied between the levers 46^a to return the shoes to their normal position when the circuit in which the solenoid is located, is 10 broken. 15

The electrical connections between the brushes 27 and the solenoid 45 with the therewith coöperative parts of the mechanism are controlled by a contact-breaking contrivance 49 the construction of which 20 will now be described.

Operatively connected with the motor-shaft 31 is a governor 48, whose sliding sleeve carries a disk 50 which engages the 25 upright arm of a bell crank 51. The opposite arm of the crank is provided with two insulated buttons 52 and 53 arranged to respectively engage with resilient contacts 54 and 55 which are secured upon the bottom 30 of the casing 37. A spring 56 serves to resiliently maintain the bell crank in engagement with the disk.

When the motor travels at high speed, the consequent inward movement of the sleeve 39, induced by the centrifugal action of the balls included in the governor, will cause the buttons 52 and 53 to engage the springs 54 and 55, while when the motor is de-energized and the rotatory movement of its 40 shaft is arrested by the brake 44, the spring 56 will cause the bell crank to follow the outward movement of the disk 50 with the result that the contact between the buttons and the springs is broken.

45 The various members of the operating mechanism which controls the movements of the curtain 7, are energized through the agency of an electro-magnetic switch 57, subsequent to the closing or breaking of the 50 main operating circuit, by means herein-after to be described.

The switch above referred to, which is best shown in Figs. 2 and 4 of the drawings, includes two electro-magnets 58 and 59 whose axes extend at right angles to each other. The armature of the first named magnet forms part of an arm 60 wholly or partially composed of insulating material, which is fulcrumed at its extremity upon a 60 standard 61. The arm 60 carries in proximity to its free extremity, two insulated buttons 62 and 63 which are normally in engagement with two superposed contacts 69 and 70 secured upon an insulating up- 75 right 64, while one of these buttons, 62, is

extended below the lower edge of the arm to engage two contacts 65 and 66 supported upon the same upright 64, when the electro-magnet 58 is energized and the arm is, in consequence, in its lower position. A spring 70 75 67 connecting the arm with an extension 68 of the upright 64, serves to maintain the former in engagement with the contacts 69 and 70 when the circuit in which the magnet 58 is placed, is broken. The armature 75 of the second magnet 59 is secured upon an upright arm 71 which is fulcrumed at 72 upon the bottom of the casing 37, and whose upper extremity is hook-shaped to engage the corresponding end of the arm 60 when the latter is in its lowermost position. A spring 73 is employed to resiliently maintain the catch 71, in its upright position when the magnet 59 is deenergized. The function of the last described portion of the switch 57, is to maintain the arm 60 in the depressed position after the magnet 58 is deenergized, until by completion of the circuit of the second magnet 59 the catch 71 is drawn from contact with the end of the horizontal arm 60. When the car approaches an intersecting street or a station the circuit by which our apparatus is operated is closed or broken by appliances the construction of which necessarily varies in 95 accordance with the nature of the vehicle on which our system is installed.

In Figs. 7 and 8 is illustrated the means used in connection with a car operated by electricity supplied through an overhead conductor 74. The transverse cable 75 from which said conductor is suspended is used as a support for a frame 76 in which a button 77 is horizontally movably disposed. A spring 78 serves to resiliently 100 maintain the button in a projected position, while any suitable means may be employed to connect the latter or the frame with which it is in contact, with the conductor 74. The harp 79 of the trolley 80 is formed with a 105 protuberance 81, into the path of which the head of the button 77 projects, and which is electrically connected with the operating circuit of our system by a wire passing through the hollow trolley pole, or other 110 means.

If so desired, a second button, similar to the one described, may be placed at the opposite side of the conductor 74 to insure the positive contact of the protuberance 81. 115 120

On cars moving along tracks equipped with a third rail 82 (see Figs. 11 and 12), a resilient contact 83 may be suspended from the guard-rail 84, to be engaged by a bevel-faced contact 85 on the arm 86 which 125 projects from the vehicle.

When the mechanism by which the curtain-movements are controlled, is actuated by the breaking instead of the closing of a circuit, the desired result may be accom- 130

plished by securing insulating strips 87 at certain intervals upon the overhead conductor 88 (see Fig. 9). The wire leading to the operating mechanism is, in this case, continuously in electrical connection with the overhead conductor except when the trolley engages the insulating strip 87, and the construction of the automatic switch 57 is modified as illustrated in Fig. 10. The electromagnet 89, in this construction, is placed above the arm 90 which is fulcrumed as in the form shown in Fig. 4 and is provided with similar buttons, similarly engaging contacts on an insulated support. The magnet is electrically connected through the trolley, with the overhead wire, by a conductor 91 and with the ground by a conductor 92. During energization of the magnet the arm is drawn in the position shown in the drawings and when the trolley passing over the strip 87 breaks the electric circuit, the said arm falls upon a suitably arranged stop 93 to break the contact between its buttons with the superposed contacts and make that with lower ones.

For the purpose of breaking the motor-circuit before the curtain has moved beyond the pre-determined distance, should the contact between the protuberance 81 and the button 77, in Fig. 7, be prolonged when the car on which the system is installed, is stopped, we have disposed a circuit-interrupting contrivance 94 in the main operating circuit. This device, as shown in Figs. 1 and 4 of the drawings, consists of a solenoid 95 whose core 96 is attached to a piston which is fitted in a dash-pot 97. The ends of the broken conductor, terminate in a contact 98 on the core 96 and a therewith continuously engaging brush 99 on the frame 100 which supports the solenoid and in case of a continued electric communication between the conductor 75 and the wire leading through the trolley pole, the core, being drawn upwardly by the electrical influence of the solenoid-coil, will carry the contact 98 out of engagement with the brush 99 and thus break the circuit.

Having thus described the mechanical construction of the various parts comprised in the mechanism by which the movements of the curtain 7 are controlled, we will now proceed to explain the electrical connections reference being had to the diagrammatical representation shown in Fig. 1, in which the various circuits employed in the system are represented by different delineations and the various mechanical and electrical devices by conventional symbols.

Let the numeral 101 designate the feeder by which the electricity required to impel the vehicle upon which our system is installed, is conducted to the overhead wire 74, from the dynamo or other source of electricity 102 whose opposite pole connects with

the ground or return conductor 103 by means of a conductor 104. The wire leading from the contact device on the trolley pole, is designated by the numeral 105 and connects through the contacts 98 and 99 of the interrupter 94, with the magnet 58 of the main switch 57. The opposite end of the electromagnetic coil 58 is connected with the ground by a wire 106 and a condenser 107 interposed between this wire and the conductor 105, serves to store electric energy while the contact is being made thereby causing the magnet to act for a prolonged period on its armature. The solenoid 95 comprised in the interrupter 94, is placed in an independent circuit, the wires 108 and 109 of which connect respectively with the wire 105 of the main operating circuit and with the ground. The releasing magnet 59 of the switch 57 is connected by a wire 110 with a conductor 112 which leads from the trolley feed wire to the contact 62 on the arm 60, and which connects by a wire 113 with one of the brushes 27 of the element A. The motor 30 is included in a circuit with the ground and the contact 62 of the switch 57, by means of wires 114 and 115; the clutch-magnet 38 is connected with the ground by a wire 116 and with the contact 66 of the switch by a conductor 117 and the solenoid 45 of the brake 44, is included in a circuit by a wire 118 leading to the brush 55 of the contact breaker 49 and a conductor 119 which connects with the contact 69 of the switch 57. The opposite brush 27 of the element A connects with the brush 54 of the governor-controlled contact breaker 49, by a conductor 120 and the two buttons 53 and 52 on the bell-crank 51 included in said device, are connected with the ground by wires 105 121 and 122. The button 63 and the contact 66 of the main switch 57 are electrically connected by a wire 123 and the contact 70 of said switch is connected by means of a conductor 124 with a non-inductive resistance 125 whose opposite pole connects with the ground by a wire 126. The function of the resistance is to save the motor 30 from injury due to induction.

In addition to the electrical devices above described, we provide a number of manually operated switches which place the entire system under absolute control of the crew of the car or train on which the system is installed. Two of these switches, designated 120 in Fig. 1 by the numerals 127 and 128, connect with the conductor 105 of the main circuit and with the wire 112 of the clutch circuit and are provided to enable the motor-man and the conductor of a car to reverse 125 the main switch 57 when it is desired to advance the curtain a distance from one station- or street-name to another. Switch 129 which like the before mentioned switches, is normally open, connects the wire 130

112 with the wire 115 of the motor circuit and is designed to allow the train-men to operate the curtain for any desired period by operation of the motor, independent of the other parts of the mechanism. The switch 130 is adapted to break the conductor 112 of the clutch circuit when it is required to discontinue the operation of the entire system and the switch 131 performs the same function of the switch 130 by breaking the conductor of the main circuit leading to the interrupter 94.

In addition to the various devices above described, fuses, resistance coils and other electrical contrivances are employed whenever required, but are for clearness of illustration, omitted from the drawings.

The operation of the system follows:— When the contact devices 81—77 by which 20 the system is included in the operating circuit of the car, are out of engagement, the contacts 69 and 70 of the main switch 57 engage the buttons 62 and 63 on the arm 60, the contact between the buttons 53 and 52 25 and the brushes 55 and 54 of the governor-controlled contact breaker, is broken and the plates 28 on the curtain engage the strips 23 so as to close the circuit in which the brushes 27 are included. Now, when the 30 protuberance 81 comes in contact with one of the buttons 77, which are located along the railway line at regular intervals between each two successive stations or intersecting streets, the magnet 58 of the main switch is 35 energized and the position of the arm 60 reversed. By the engagement of the button 62 on the latter with the contacts 65 and 66, the motor circuit as well as the clutch circuit are closed and the consequent rotatory movement of the shaft 31 is transmitted by means 40 of the chain 43, to the roller 4 of the element A with the result that the curtain 7 is moved vertically before the window 8 in the casing 2. At the beginning of this movement, before the motor-shaft has attained sufficient velocity to bring the contacts 52 and 53 in engagement with the brushes 55 and 54 through the instrumentality of the 45 governor 48, the plates 28 move from contact with the strips 23 on the roller 5 and the curtain will, in consequence, continue to move until the next set of plates, which are placed along the curtain at distances equal to those between the street names, comes in 50 contact with the strips 23, when the releasing magnet 59 is energized. By action of this magnet the catch 71, which retained the arm 60 in its depressed position, is drawn rearwardly and releases the same with the result that the buttons 62 and 63 are again brought in engagement with the contacts 69 and 70 and the motor and clutch-circuits are broken. The solenoid 45 of the brake 44 is, at the same time, energized through the contact of the parts 62 and 69

and the motor is thereby brought to a sudden stop while the governor 48 whose balls move inwardly by reason of the reduced speed of the shaft 31, causes the contact between the buttons 53 and 52 and the springs 55 and 54 to be subsequently broken. The parts are thus returned to their original position, ready to again move the curtain a distance equal to that between two consecutive street names on its outer surface 75 or between two consecutive sets of contact plates on its inner side.

In case a car on which our system is installed, is stopped with the contact devices on the trolley and overhead wire, or on the third rail, as the case may be, in engagement, the solenoid 95 of the interrupter 94, whose action is considerably slower than that of the magnet 58 of the main switch, will cause the contact 98 on the core 96 to disengage the brush 99, thus breaking the operating circuit, and the parts included in the interrupter are proportioned so that the time required in the above action is approximately equal to that in which the curtain 7 moves the required distance. After the interrupter circuit is broken, the core controlled by the dash-pot 97, will return to its original position.

The operation of the system, when instead of closing the circuit to actuate the motor, the same is opened, has been described hereinbefore and requires no further explanation at this point, and it is obvious that on storage battery cars or wherever desired, a switch within reach of the motorman or conductor, may be substituted for either the trolley or 3rd rail contact devices, to close the motor-circuit each time a street intersecting the line of railway is approached.

It should furthermore be understood that when our system is employed on large cars or on trains made up of several vehicles, a number of the indicative elements A may 110 be connected so as to operate synchronously by connection with one contact device.

Having thus described our invention, what we claim and desire to protect by Letters Patent is:—

1. A station indicating system comprising a movable curtain, a motor adapted to actuate the same, a switch in the motor circuit, electric means for actuating said switch in a shunt circuit of the operating circuit of an electric railway, a conductor of electricity included in said operating circuit, a contact device adapted to close said shunt-circuit by engagement with said conductor of electricity at determinate points thereof, and an interrupter in said shunt circuit, adapted to open the same after a determined period of contact of said device with said conductor.

2. A station indicating system comprising

a movable curtain, a motor adapted to actuate the same, a switch in the motor circuit, electric means for actuating said switch in a shunt circuit of the operating circuit of an electric railway, a contact device adapted to close said shunt circuit by engagement with a conductor of electricity of said operating circuit at determinate points thereof, and an interrupter comprising a solenoid whose core 5 carries a terminal of said shunt circuit, and a stationary contact normally engaging said terminal and connected with the opposite terminal of said circuit.

3. A station indicating system comprising a movable curtain, an electric motor adapted to actuate the same, an electrically actuated clutch adapted to operatively connect the driving part of said motor with the driven part by which said curtain is actuated, an 15 electric switch in circuits with said motor and with said clutch, electric means for operating said switch whereby said motor and said clutch are simultaneously actuated, an electric device adapted to automatically 20 maintain said switch in its circuit closing position and to release the same when the circuit in which said device is located, is closed, and contacts associated with said curtain to close the last named circuit at 25 determinate points of the movement of the curtain.

4. A station indicating system comprising a movable curtain, a motor for actuating the same, an electric switch in the motor circuit, 30 electric means for operating the switch, an electric brake for retarding the movement of the motor shaft, electric means for actuating said brake, after the curtain has traveled a determined period, and a device connected 35 with the motor to deenergize said electric means when the velocity of the motor is reduced to a determined degree.

5. A station indicating system comprising a movable curtain, a motor adapted to 40 actuate the same, an electric switch in the motor-circuit, electric means for operating said switch, an electric device adapted to automatically maintain said switch in its circuit closing position and to release the 45 same when the circuit in which said device is located, is closed, contacts associated with said curtain to close the last named circuit at predeterminate points of the movement of the curtain, and a contact breaking contrivance in said last named circuit, operatively connected with a driving part of the motor and adapted to break its circuit when the velocity of the motor is reduced to a predeterminate degree.

60 6. A station indicating system comprising a movable curtain, a motor adapted to actuate the same, an electric switch in the motor-circuit, electric means for operating said switch, an electric device adapted to automatically maintain said switch in its cir-

cuit closing position and to release the same when the circuit in which said device is located, is closed, contacts associated with said curtain to close the last named circuit at determinate points of the movement of the curtain, and a contact breaking contrivance in said last named circuit and comprising a governor operatively connected with the motor shaft, normally separated movable and stationary contacts in which said circuit terminates, and a means on said governor whereby said movable contact is brought in engagement with the stationary one during movement of the shaft beyond a determinate degree of speed.

7. A station indicating system comprising a movable curtain, a motor adapted to actuate the same, an electric switch in the motor-circuit, electric means for operating said switch, an electric device adapted to automatically maintain said switch in its circuit closing position and to release the same when the circuit in which said device is located, is closed, contacts associated with said curtain to close the last named circuit at determinate points of the movement of the curtain, an electric brake in a circuit controlled by said switch, a movable contact normally breaking the brake-operating circuit and the circuit of the switch-releasing device, and a governor on the motor-shaft adapted to actuate said contact so as to close said circuits when the velocity of said shaft exceeds a determinate degree.

8. A station indicating system comprising a movable curtain, a motor adapted to actuate the same, an electric brake adapted to retard movement of the movable parts of the latter, an electrically actuated clutch adapted to connect said parts with the driven part by which the curtain is actuated, an electric switch normally opening the motor circuit and the clutch-circuit and closing the brake circuit, electric means for reversing said switch, an electrically actuated device to automatically maintain said switch in its reversed position and to release the same when the circuit in which said device is located, is closed, and contacts associated with said curtain to close the last named circuit at determinate points of the movement of the curtain.

9. A station indicating system comprising a movable curtain, a motor adapted to actuate the same, an electric brake adapted to retard movement of the movable parts of the latter, an electrically actuated clutch adapted to connect said parts with the driven part by which the curtain is actuated, an electric switch normally opening the motor circuit and the clutch-circuit and closing the brake circuit, electric means for reversing said switch, an electrically actuated device to automatically maintain said switch in its reversed position and to release the same

when the circuit in which said device is located, is closed, contacts associated with said curtain to close the last named circuit at determinate points of the movement of 5 the curtain, a contact breaker controlling said last named circuit and the brake-circuit, and a governor connected with the motor-shaft and adapted to engage said contact-breaker so as to close said circuits when the 10 velocity of said shaft exceeds a determinate degree.

10. A station indicating system comprising a casing, parallel shafts rotatably mounted therein, rollers revolvably mounted 15 on said shafts, a curtain connected with said rollers to move from one onto the other, an electric motor adapted to actuate one of said shafts, a coiled spring connected at its opposite ends with the other shaft and with the roller mounted thereon, a clutch normally connecting the first named shaft with the roller carried thereby, and manual means for releasing said clutch from said roller.

15. 11. A station indicating system comprising a movable curtain, a motor adapted to actuate the same, an electric brake adapted to retard the moving parts of the latter, an electrically actuated clutch adapted to con-

nect said parts with the driven parts by 30 which the curtain is actuated, a switch normally opening the motor-circuit and the clutch circuit and closing the brake circuit, electric means for reversing said switch, in a shunt circuit of the operating circuit of 35 an electric railway, a conductor of electricity included in said operating circuit, a contact device adapted to close said shunt circuit by engagement with said conductor at determinate points thereof, an interrupter in said 40 shunt circuit adapted to open the same after a determined period of contact of said device with said conductor, an electrically actuated device to automatically maintain said switch in its reversed position and to release the same when the circuit in which said device is located, is closed, and contacts associated with said curtain to close the last named circuit at determinate points of the movement of the latter.

In testimony whereof we have affixed our signatures in presence of two witnesses.
